US0D1025120S

(12) United States Design Patent (10) Patent No.: US D1,025,120 S
 Visser et al. (45) Date of Patent:  Apr. 30, 2024

(54) DISPLAY SCREEN OR PORTION THEREOF WITH GRAPHICAL USER INTERFACE(71) Applicant: Aristocrat Technologies Australia Pty Limited, North Ryde (AU)(72) Inventors: Antoon Visser, Coogee (AU); Lin Liu, North Ryde (AU); Lauren Paterson, Kellyville (AU); Benjamin Tinworth, Wollstonecraft (AU)(73) Assignee: Aristocrat Technologies Australia Pty Limited, North Ryde (AU)() Term: 15 Years(21) Appl. No.: 29/850,206(22) Filed: Aug. 17, 2022*Related U.S. Application Data

(63) Continuation of application No. 29/809,073, filed on Sep. 24, 2021, now Pat. No. Des. 965,024, which is a continuation of application No. 29/782,345, filed on May 6, 2021, now Pat. No. Des. 965,023, which is a continuation of application No. 29/722,810, filed on Jan. 31, 2020, now Pat. No. Des. 922,409, which is a continuation-in-part of application No. 16/779,540, filed on Jan. 31, 2020, now Pat. No. 10,872,502.

(57) CLAIM

The ornamental design for a display screen or portion thereof with graphical user interface, as shown and described.

DESCRIPTION

FIG. 1 is a front view of a display screen or portion thereof with graphical user interface showing our new design according to a first embodiment;

FIG. 2 is a front view of a display screen or portion thereof with graphical user interface showing our new design according to a second embodiment;

FIG. 3 is a front view of a display screen or portion thereof with graphical user interface showing our new design according to a third embodiment;

FIG. 4 is a front view of a display screen or portion thereof with graphical user interface showing our new design according to a fourth embodiment; and,

FIG. 5 is a front view of a display screen or portion thereof with graphical user interface showing our new design according to a fifth embodiment.

The dashed broken line perimeter in the drawings illustrates a display screen or portion thereof and forms no part of the claimed design. The remaining dashed broken lines in the drawings illustrate portions of the graphical user interface that form no part of the claimed design.

1 Claim, 5 Drawing Sheets
